UNITED STATES PATENT OFFICE.

CARL THOMAS MASON, OF EAST ORANGE, NEW JERSEY, ASSIGNOR TO SPLITDORF ELECTRICAL COMPANY, OF NEWARK, NEW JERSEY, A CORPORATION OF NEW JERSEY.

IGNITION SYSTEM FOR INTERNAL-COMBUSTION ENGINES.

1,260,985.

Specification of Letters Patent. Patented Mar. 26, 1918.

Application filed September 29, 1916. Serial No. 122,860.

To all whom it may concern:

Be it known that I, CARL THOMAS MASON, a citizen of the United States, residing at East Orange, in the county of Essex and State of New Jersey, have invented certain new and useful Improvements in Ignition Systems for Internal-Combustion Engines, of which the following is a specification, reference being had to the accompanying drawing.

The invention relates to ignition systems for internal combustion engines, and more particularly to the starting ignition when the engine is being turned over slowly either by hand or other starting means.

An object of the invention is to provide an ignition system wherein the sparking voltage is furnished by a high tension magneto or magnetos having primary and secondary windings, and wherein the current for the primary winding during the slow running of the engine at starting is furnished to the magneto from an independent low tension magneto which is operated from the crank means for the engine.

A further object of the invention is to provide an ignition system of the above character wherein the low tension magneto is driven at a greater speed than the engine shaft while generating current for the primary winding of the high tension or main ignition magneto.

These and other objects will in part be obvious and will in part be hereinafter more fully disclosed.

In the drawings, which show by way of illustration one embodiment of the invention:—

Figure 1 is a view showing, more or less diagrammatically, an ignition system embodying my improvements;

Fig. 2 is a diagrammatic view, showing the circuit connections of my improved system.

The invention consists in an ignition system having a high tension magneto or generator for furnishing the sparking voltage for the engine during the normal running of the engine. One or more magnetos of this type may be used, as desired. These magnetos are positively driven by the means of gears or the like so that they are always in proper timing with the engine. Associated with each magneto is the usual dis-

tributer, when said magnetos are used in connection with a multiple cylinder engine. Also associated with these magnetos and for starting purposes is an auxiliary magneto which has a single winding connected through suitable switches with the primary winding of one of the main high tension magnetos.

The armature of this auxiliary starting magneto is adapted to be connected with the starting mechanism for turning over the engine so as to be driven thereby. This low tension starting magneto, even when driven at the low speed of the turning of the engine shaft for starting, generates sufficient current so as to produce the required starting voltage in the secondary of the main magneto furnishing ignition for the engine. The connection between the armature of the starting magneto and the cranking mechanism may be such as to drive the armature of the magneto at a much greater speed than the speed of the engine shaft during starting.

Referring more in detail to the drawings:—

The improved ignition system consists of two main ignition magnetos of a high tension type, indicated at 1 and 2 in the drawings. The structure of these magnetos is identical, and each consists of a primary winding *p* and a secondary winding *s*. The secondary winding is connected to the core *c* at one end thereof, and the core is grounded, as indicated diagrammatically in Fig. 2 of the drawings. The other end of the secondary winding is connected with a distributor *d* which is in turn connected to the spark plugs of the engine. The magnetos are provided with the usual interrupters, indicated at *i* for the primary circuit and the condenser indicated at *e*. These magnetos are geared to the engine shaft so as to be positively driven thereby and in proper timing with the engine.

During the starting of the engine, the engine shaft is turned very slowly and the current generated in the primary of the main magnetos 1 and 2 may not be quite sufficient to produce the desired voltage in the secondary winding for sparking, and I have, therefore, associated with these main magnetos an auxiliary starting magneto of the low tension type which is indicated at 3. This magneto 3 is, as herein shown, mounted

adjacent the end of the engine shaft, which is adapted to be turned by a crank 4 for starting. The armature of the magneto 3 is provided with a pinion 5. The crank 5 carries a pinion 6. When the crank is pushed in for clutching engagement with the armature shaft, the pinion 6 is caused to mesh with the pinion 5, said pinion 6 being normally out of engagement with the pinion 5. The pinion 6 is preferably considerably larger than the pinion 5 so as to rotate the armature shaft of the magneto 3 at considerably greater speed than the engine shaft. Preferably these gears are so proportioned 15 as to drive the armature shaft of the engine four revolutions for every single revolution of the engine shaft.

This starting magneto is of the ordinary low tension variety and is provided with a 20 winding indicated at 7. The current generated in the winding 7 during the turning over of the engine shaft for starting is carried to the primary of one or the other of the magnetos 1 and 2. One terminal of the winding 7 is grounded, while the other terminal is connected to a line 8 which leads to a switch S. Said switch is provided with a segmental plate 9 with which the conductor 8 is attached. Said switch is also provided with a terminal 10 which is connected through the conductor 11 with the primary p of the magneto 1. The switch has a second terminal 12 which is connected through the conductor 13 in the primary p of the magneto 2. Said switch is provided with 25 movable contacts 14 and 15 which are connected with the segment 9, as indicated diagrammatically in the drawings. When the contact 14 is brought into engagement with the terminal 10, then the segment 9 is connected with the primary of the magneto 1, and thus the winding of the low tension magneto 3 is connected with the magneto 1. When the contact 15 is connected to the terminal 20, then the winding 7 of the magneto 3 will be connected to the magneto 2. If a single magneto is used, then, of course, this switch will be modified accordingly.

50 In the operation of my improved ignition system, the crank 4 is connected to the engine shaft for starting the engine, and as the engine shaft is turned over the armature of the auxiliary starting magneto 3 will be rotated. The current generated in the winding 7 will pass through the switch S to one or the other of the main high tension magnetos, and the current thus furnished to the primary of the high tension magneto will generate a sparking voltage in the secondary of said high tension magneto, which will be furnished to the proper cylinder through the distributor coöperating with said magneto. As soon as the engine has started,

then the switch is thrown so as to disconnect 65 the auxiliary magneto from the main high tension magnetos, and these main high tension magnetos will generate the sparking voltage for the engine.

While I have shown the auxiliary starting 70 magneto operated from a hand cranking mechanism, it will be understood that it may be used in connection with any cranking mechanism for the engine. By using this low tension magneto sufficient current 75 may be generated for obtaining through the secondary of a high tension magneto sufficient voltage for sparking purposes although the engine shaft is moving very slowly. As soon as the engine shaft is operated from the power of the engine, then the main high tension magnetos will have sufficient speed imparted to the armatures to furnish the proper current sparking voltage for ignition.

It is obvious that minor changes in the details of construction and the arrangement of parts may be made without departing from the spirit of this invention, as set forth in the appended claims.

Having thus described the invention, what is claimed as new is:—

1. An ignition system for internal combustion engines comprising an ignition mechanism including a main high tension magneto driven by the engine and having a primary and a secondary winding for furnishing sparking voltage, a starting low tension magneto having a winding adapted to be connected to the primary of the high tension magneto for furnishing current thereto, and means for operating said starting magneto from the cranking means for the engine.

2. An ignition system for internal combustion engines comprising an ignition mechanism including a main high tension magneto driven by the engine and having a primary and a secondary winding for furnishing sparking voltage, a starting low tension magneto having a winding adapted to be connected to the primary of the high tension magneto for furnishing current thereto, and means for operating said starting magneto from the cranking means for the engine, including devices for revolving the armature of said starting magneto at a greater speed than the engine shaft.

3. An ignition system for internal combustion engines including in combination a high tension magneto having a primary and a secondary winding for furnishing sparking voltage, a low tension starting magneto having a winding adapted to be connected to the primary of the high tension magneto for furnishing current thereto, a gear connected with the crank for cranking the engine and turning therewith, and a gear on

the armature shaft of the starting magneto adapted to mesh with the gear on the crank when said crank is in engagement with the engine shaft, said gears being so proportioned as to turn the armature shaft of the magneto at a greater speed than the engine shaft.

In testimony whereof I hereunto affix my signature in the presence of two witnesses.

CARL THOMAS MASON.
